UNITED STATES PATENT OFFICE

2,042,988

DYNAMIC MULTIPLIER

John Hays Hammond, Jr., Gloucester, Mass.

Application February 15, 1933, Serial No. 656,814

11 Claims. (Cl. 179—100.1)

This invention relates to amplifying systems and more particularly to an improved method of controlling the amount of amplification in accordance with the strength of the applied energy.

5 The invention relates particularly to a system of amplification in which a greater ratio of amplification or gain is produced for impressed signals of high intensity than for impressed signals of low intensity whereby the volume range of the 10 signal is expanded.

The present invention provides for controlling the operating characteristics of sound reproducing or recording devices in accordance with the strength of the applied signal. As applied to an 15 electromagnetic reproducing or recording device the invention provides for varying the field strength of the device according to the general energy level of the signal so as to produce relatively more response to loud signals than to weak signals whereby the sound range of said device is 20 expanded.

The invention also consists in certain new and original features of construction and combinations of parts hereinafter set forth and claimed.

25 Although the novel features which are believed to be characteristic of this invention will be particularly pointed out in the claims appended hereto, the invention itself, as to its objects and advantages, the mode of its operation and the 30 manner of its organization may be better understood by referring to the following description taken in connection with the accompanying drawing forming a part thereof, in which

The figure illustrates diagrammatically the 35 system as applied to the reproduction of the sound record of either a talking moving picture film or a phonograph record, or to the recording of a sound record.

In the following description and in the claims, 40 parts will be identified by specific names for convenience, but they are intended to be as generic in their application to similar parts as the art will permit.

45 Referring more particularly to the drawing a light source 10 is provided, the light from which is focused by a lens 11 through an aperture 12 in an aperture plate 13 and upon the sound record of a moving photographic film 14. The light which passes through this film is focused by a 50 second lens 15 upon a photoelectric cell 16. This cell is connected through a battery 17 to the primary of a transformer 18 the secondary of which is connected in the input circuit of a space discharge amplifier 19 of well known form. The 55 output circuit of this amplifier includes the pri-

mary of a transformer 21, one side of the secondary of which is connected to one contact 121 of a three position switch 22.

A phonographic pick-up device 23 for use with a disc record is provided, which includes an armature coil 123 and a field coil 124. One side of the armature coil 123 is connected to the second contact 125 of the switch 22.

A microphone 126 is provided for sound recording purposes and is connected to the primary of a transformer 127. One side of the secondary of this transformer is connected to the third contact 128 of the switch 22.

The blade of the switch 22 is connected to the grid of a space discharge device 24, the cathode 15 of which is connected through a biasing battery 28 to the other side of the armature coil 123 of the phonograph pick-up 23, and to the other sides of the secondaries of the transformers 21 and 127.

The output circuit of the device 24 includes the 20 primary of a transformer 25 the secondary of which is connected across a potentiometer 26. The adjustable contact of the potentiometer 26 is connected to the grid of a space discharge device 27, the devices 24 and 27 being provided with 25 a common biasing battery 28, filament battery 29, and plate battery 30.

The output circuit of the device 27 is connected to the primary of a transformer 32, the secondary of which is connected to the input circuit of a 30 push-pull amplifier 33. The output circuit of this amplifier 33 is connected to the primary of a transformer 34 provided with two secondaries 35 and 36. The secondary 35 is alternately connected by means of a single pole double throw 35 switch 135 to the armature coil 37 of a loud speaker 38 of well known form, and to the armature coil 136 of a phonographic engraving tool 137, which is also provided with a field coil 138.

The secondary 36 is connected in a circuit including two resistances 41 and 42, and a rectifier 43 which permits current to flow in resistance 42 in the direction of the arrow. The resistance 42 may be shunted by a condenser 44 adapted to control the time characteristics of the current flowing therein. The resistance 42 is connected in the input circuit of a space discharge device 45 to control the biasing potential of the device 45 according to the potential drop across said resistance 42. The connection is shown as such 50 that an increase in current in resistance 42 increases the negative biasing potential on the device 45 and thereby reduces the current in the plate circuit thereof. The output circuit of space discharge device 45 includes a secondary winding 55

48 of a transformer 47, the primary of which is connected to a source of A. C. supply 51, and a resistance 48 shunted by a condenser 49. The secondary 46 constitutes a source of plate current for the device 45. The resistance 48 is connected in parallel in the input circuits of two space discharge devices 52 and 53 and determines the biasing potential thereon. The filaments of the devices 45, 52 and 53 are heated by current from a secondary winding 54 of the transformer 47.

The plates of the devices 52 and 53 are connected across a secondary winding 55 of the transformer 47 which serves as a source of space current therefor and to the field winding 56 of the loud speaker 38 and the field winding 138 of the engraving tool 137, in parallel. The return leads of the field windings 56 and 138 are connected to the mid-point of the secondary 54. A condenser 57 may be shunted across the field winding 56 to control the operating characteristics of the loud speaker 38.

The field winding 124 of the phonograph pick-up 23 is selectively connected by a single pole, double throw switch 64 to a battery 62 or, in parallel with the field winding 56, in the output circuit of space discharge devices 52 and 53. A variable resistance 61 may be included in circuit with the winding 124 to control the energization thereof.

In the operation of the above described system the switch 22 is thrown into engagement with the contact 121 when it is desired to use the sound film 14. When it is desired to use the phonograph pick-up 23 the switch 22 is thrown into engagement with the contact 125 and when it is desired to use the microphone 126 it is thrown into engagement with the contact 128. In any case sound energy from one of these sources is fed to the input circuit of the space discharge amplifier 24, where it is amplified and fed through the transformer 25 to the space discharge device 21. Here it is further amplified and fed through the transformer 32 to the push-pull amplifier 33. A large part of the output of this amplifier passes through the secondary 35 to the armature coil 136 of the engraving tool 137, or to the coil 37 of the loud speaker 38, depending on the position of the switch 135. The rest of the energy passes to the control circuit through the secondary 36 and causes current to flow through the resistance 42 in the direction of the arrow.

When no signal is being received, no current will flow through the resistance 42 and therefore no negative potential will be applied to the grid of the device 45. Under these conditions the device 45 is adapted to pass a large pulsating current through the resistance 48 in the direction of the arrow, thereby building up a large negative potential on the grids of the devices 52 and 53 adapted to increase the impedance thereof so as to reduce the current flowing in the output circuit including field winding 56 or 138. Therefore the volume of sound emitted by the loud speaker 38 or the energy recorded by the tool 137 will be at a minimum. Condenser 44 controls the operating time characteristics of the control circuit so that the control is responsive to the average energy level of the sound responsive means over a predetermined interval of time corresponding to, for example, the rate of change in sound level as distinguished from the instantaneous energy level of the sound waves.

When a large signal is received the current

flowing through the resistance 42 will be large and a high negative potential will be applied to the grid of the device 45, thus increasing its impedance and cutting down the current flowing through this device and through the resistance 48. This will decrease the negative potential applied to the grids of the devices 52 and 53, thus allowing these devices to pass a large amount of current which will flow through the field windings 56 or 138 and increase the volume of sound emitted by the loud speaker 38 or the energy recorded by the engraving tool 137.

With the switch 64 down (in the arrangement illustrated), part of the current from the devices 52 and 53 will flow through the field winding 124 of the phonograph pick-up 23. When the input signal is weak this current will be small, so that the magnetic flux of the pick-up 23 will be low. The currents induced in the armature winding 123 of this device will, therefore, be decreased, thus decreasing the input energy to the amplifier 24 which will still further reduce the volume of sound produced by the loud speaker 38.

When the input signal is strong, a large amount of current will flow through the winding 124, thus increasing the magnetic flux produced, which in turn will increase the currents flowing through the armature winding 123 of the pick-up 23. This will increase the input energy to the amplifier 24, thus increasing the energy fed to the armature coil 37 of the loud speaker 38, thereby further increasing the volume of sound produced by this device.

If it is desired to use the pick-up 23 in a standard manner, the switch 64 is thrown to the up position, thus connecting the battery 62 across the field 124 and thereby producing a constant magnetic flux in the field of this device.

It is thus seen that this system provides a means whereby the volume of sound emitted by the loud speaker 38 or recorded by the engraving tool 137 is less on weak signals and greater on strong signals than it would be if the field windings of the loud speaker 38 and engraving tool 137 were uniformly energized by a constant field current. In this way it is possible to increase the dynamic range of the loud speaker or the recording device.

It is also possible to increase this range by controlling the magnetic flux of the pick-up device, thus producing a regenerative action which greatly increases the strength of the strong signals and decreases the strength of the weak signals.

It is to be understood that the loud speaker 38 or the engraving tool 137 are illustrative only and may be replaced by any suitable and well known device for recording sound, for example, on a moving photographic film or the like.

Although only one of the various forms in which this invention may be embodied has been shown herein, it is to be understood that the invention is not to be limited to any specific construction, but may be embodied in various forms without departing from the spirit of the invention or the scope of the appended claims.

What is claimed is:

1. In a sound translating system, means responsive to sound energy, amplifying means adapted to amplify said sound energy, a sound reproducing device, a sound recording device, means to actuate either of said devices in accordance with the instantaneous value of said amplified energy and means to modify the actuation

- thereof in accordance with the average value of said energy over a predetermined time interval.
2. In a sound record system, input means responsive to sound energy, translating means actuated thereby, an output device actuated by said translating means, and means controlled by the average energy level to vary the response characteristics both of said input means and of said output device.
- 10 3. In a sound record system, means responsive to sound energy adapted to translate said sound energy into electrical energy, a space discharge amplifier therefor, a utility responsive to said electrical energy, said utility having a variable magnetic field adapted to control its response characteristics, and means to energize said field in accordance with the average level of said sound energy over a predetermined time interval and an independent source of space energy for said amplifier.
- 20 4. In a sound record system, means responsive to sound energy adapted to translate said sound energy into electrical energy, a space discharge amplifier therefor, a utility responsive to said electrical energy, said utility having a variable magnetic field adapted to control its response characteristics, a source of energizing current for said field, and means to control said current in accordance with the average value of said electrical energy over predetermined time intervals and an independent source of space energy for said amplifier.
- 30 5. In a sound record system, means responsive to sound energy adapted to translate said sound energy into electrical energy, a space discharge amplifier therefor, a utility responsive to said electrical energy, said utility having a variable magnetic field adapted to control its response characteristics, an energizing winding for said field, a space discharge device, means to pass the space current of said device through said winding to energize the same, and means to control said space current in accordance with the energy level of the sound source and an independent source of space energy for said amplifier.
- 40 6. In combination, a pick-up device adapted to be actuated by a sound record, amplifying means actuated by said device, a utility actuated by said amplifying means, means to control the response

characteristics of said pick-up device and of said utility, and means controlled by the energy level of said sound record to actuate said control means whereby the response of said pick-up device and of said utility is increased at high energy levels 5 and vice versa.

7. In a system of the class described, a pick-up device adapted to be actuated by a sound record, space discharge amplifying means actuated in response to energy translated by said pick-up 10 means, a loud speaking device having an armature coil and a field coil, said armature coil being actuated by energy derived from said amplifying means, a second space discharge means, means controlling said second space discharge means in 15 accordance with the average level of said energy and means controlled by said second space discharge means for controlling the energization of said field coil.

8. The method of reproducing sound from a 20 sound record which comprises translating said record into electrical energy, amplifying said electrical energy, applying said amplified electrical energy to a loud speaker and controlling the response characteristics of said loud speaker 25 in accordance with the average energy level in such a manner that the volume ratio of the reproduced sound waves is altered with respect to the indicated volume ratio of said record.

9. In combination, a first translating device 30 having an armature winding and a field winding, a second translating device fed thereby, and means for energizing the field winding of said first translating device according to the energy from the armature winding thereof. 35

10. In combination, a first translating device, a second translating device fed by said first device, a magnetic field in said first translating device and means for controlling the strength of said field according to a moving average of the 40 energy from said first translating device.

11. In combination, a first translating device, a second translating device fed by said first device, magnetic fields in both said translating devices and means for controlling the strength of 45 said fields according to a moving average of the energy from said first translating device.

JOHN HAYS HAMMOND, JR.
